UNITED STATES PATENT OFFICE.

JEROME J. MILLER, OF CHADRON, NEBRASKA.

PENCIL SHARPENER.

Application filed April 12, 1926. Serial No. 101,495.

My present invention relates generally to compound tools of the character described and claimed in my Patent 1,479,921, dated Jan. 8, 1924, for a device capable of utilizing safety razor blades, whose principal function is the sharpening of pencils.

My present invention proposes a somewhat similar arrangement, which has for its particular function the sharpening of pencils, and which has for a further object the sharpening of pencils in such manner as to reduce to a minimum the danger of breaking the lead.

A still further object is the provision of a device of this character having means adapting the same for use as a paper cutter, as well as one wheréin the pencils may be sharpened by a trimming of the wood portion of the pencil without the usual trimming of the lead.

It is a well known fact that in connection with most hand pencil sharpeners wherein the pencil is inserted in the bore of a block or holder and rotated against the edge of a stationary cutter, the primary cause of such frequent breakage of the lead is the fact that the lead along with the wooden portion of the pencil is at the same time forced against the cutting edge.

In my present arrangement the lead of the pencil is not cut during the cutting of the wood portion of the pencil, but is left cylindrical or substantially so for subsequent shaving to a more or less fine point, as may be desired.

In the accompanying drawing which illustrates my present invention and forms a part of this specification:—

Figure 1 is a perspective view showing my improved combination tool.

Figure 2 is a top plan view thereof.

Figure 3 is a side elevation thereof, and, Figure 4 is an end view looking toward the entrance of the bores into which the pencils are inserted for sharpening in the first instance, the block being partly in section.

Referring now to these figures, my invention proposes a combination tool of the type specified, which includes a body generally in the rectangular form of a block as seen at 10, the upper surface of which is provided with a broad lengthwise channel having a flat bottom or floor 11 for the reception of a safety razor or other blade 12, the latter held in place by a cap plate 13. This cap plate is secured in place upon the blade 12 by virtue of a threaded stud rising from the block 10 at a point approximately at the center of the

channel 11, the stud extending through an opening in the blade 12 and through a slot 14 of the cap plate 13, in order to receive a clamping nut 15, which bears directly upon the cap plate.

Along the sides of the channel 11 for the major portion of the length are a pair of tapering pencil receiving bores 16 which enter one end of the body or block 10, the latter having slots in communicating with the channel at the sides in which the sharpened side edges of the blade 12 extend when the latter is properly secured upon the bottom of the channel 11 through the use of the cap plate 13 and the clamping nut 15. It will be noted from Fig. 3 in particular that the axes of the bores 16 are disposed at such angles relatively to the bottom of the channel 11, that the leads of pencils may extend in the cutting operation into cylindrical inner end extensions 17 of these bores, while the pencils are being rotated against the cutting edges of the blade 12, and it will be noted from Figs. 1 and 2 that the blade 12 as well as the cap plate 13 have side recesses at 18 disposed opposite to the inner cylindrical extensions 17 of the bores 16 so that the leads of the pencils extending into these bores cannot come into contact with any portion of the blade 12 or cap plate 13.

Thus in the operation of the pencil sharpener the wood portions of pencils alone will be cut by the side edges of the cutting blade and the leads of the pencils will be left cylindrical or substantially so in order to reduce to a minimum the danger of breakage. The leads may subsequently be reduced by cutting or otherwise, in order to more or less point them as may be desired, and for this purpose the leads may be drawn laterally across one edge of the blade 12 opposite a transverse groove 19 formed in one side of the upper surface of the body or block 10 to receive the leads.

It is for a similar purpose that the base or lower surface of the block 10 is slightly curved to present a convex face which is knurled or otherwise treated to form a file surface 20 upon which the leads may be pointed or may be dressed and sharpened after substantial pointing within the groove 19 against the adjacent portion of one edge of the blade 12.

It will also be noted in particular from Figs. 1 and 2 that one corner of the body or block 10 and at that end of the latter opposite

the entrance of the bores 16, is cut away on an angle as indicated at 21, and at such an angle as to allow for adjustment of the blade 12 to bring one corner of the blade in slightly 5 projecting relation beyond and intermediate the ends of the obliquely or slantingly cut corner 21. In this way I adapt the device to use of the paper cutter in which use it may be guided along a ruler or other guide across 10 the paper. In this movement the slanting or obliquely cut corner of the block is maintained parallel or substantially parallel with the paper to be cut so that the projecting corner of the blade 12 may enter and sever the 15 paper along the desired line. Obviously, under ordinary circumstances the blade 12 may be adjusted so that no portion thereof projects beyond the slanting surface of the block and the user may thus avoid accidental cutting 20 of the hands and clothing.

It is also obvious that by shifting the blade 12 lengthwise as far as possible beyond the end of the block or body of the tool, it may be employed similar to a knife. By shifting the 25 blade to present a portion of its edge opposite the recess 18 of the clamping plate 13, the lead of a pencil may be sharpened in the extension 17 of one of the block bores.

I claim:—

30 1. A pencil sharpener comprising a block of rectangular form having a channel extending length-wise in its upper face from end to

end, defining longitudinal ribs at the sides thereof, longitudinal bores at the sides opening into said channel, a blade adjustably fitted within said channel, the opposite cutting edges of which project into said channel side openings, said bores having reduced cylindrical extensions at their inner ends, and at a slight angle to the major axis of the bores, 35 said bores having their major axes inclined in said body block, said inner cylindrical extensions having their axes substantially parallel to said channel, the cutting edges of said blades having recesses adapted to be positioned opposite the said cylindrical extensions, and means for adjustably holding the blade in operative position.

2. A pencil sharpener, comprising a base block having a channel extending lengthwise 50 of its upper face and defining a longitudinal rib at a side thereof, a longitudinal bore at the side and opening into said channel, said bore being inclined and having a reduced cylindrical extension at the inner end at a 55 slight angle to the major axis of the said bore, a cutting blade removably held in said channel, the cutting edge of said blade projecting into the said channel side opening, the cutting edge of said blade having a recess adapted to 60 be positioned opposite the reduced cylindrical extension.
